(57) **CLAIM**

The ornamental design for a computing device as shown and described.

DESCRIPTION

FIG. 1 is a rear perspective view of a computing device showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof; and,

FIG. 9 is a front perspective view thereof.

The even-length broken lines shown in the drawings depict portions of the computing device that form no part of the claimed design. The dot-dash broken lines shown in the drawings depict the boundaries of the claim and form no part of the claimed design.
